UNITED STATES PATENT OFFICE.

DON O. MARKS, OF LOS ANGELES, CALIFORNIA, ASSIGNOR OF ONE-HALF TO LYNN S. ATKINSON, OF COLORADO SPRINGS, COLORADO.

CENTRIFUGAL-IMPACT PULVERIZER.

982,516.

Specification of Letters Patent. Patented Jan. 24, 1911.

Application filed May 23, 1907. Serial No. 375,345.

To all whom it may concern:

Be it known that I, DON OTTO MARKS, a citizen of the United States of America, residing at Los Angeles, in the county of Los Angeles and State of California, have invented certain new and useful Improvements in Centrifugal-Impact Pulverizers, of which the following is a specification.

An object of this invention is to provide a superior machine for disintegrating and pulverizing or reducing frangible materials such as ore, rock, sand, shells, bone, coal, coke, pepper, spices, coffee, grain, fruit, and other substances which it is desired to reduce 15 to a pulp or to a powdered state.

This invention relates to that class of machines in which centrifugal force and impact are utilized to effect the disintegration and pulverization or reduction of the materials 20 or objects to be reduced. I provide a machine whereby the reduction may be accomplished by application of centrifugal force for driving the material or substance to be pulverized, with great force against a wall 25 suitably constructed and arranged to suddenly intercept the material, and to cause the same to become disintegrated and pulverized or reduced to a pulp or other fine state by the force of its own momentum; 30 means being provided for discharging the product so that the operation of the machine may be continuous.

The device by which motion is imparted to the material to be reduced, may be constructed to operate as a blower by which any dry product will be discharged from the machine, as well as an impeller for the materials or objects to be reduced.

An object of this invention is to produce a 40 granular product of any desired fineness at the least expenditure of power and time.

A further object of the invention is to provide for frangible substances of great hardness and abrasive qualities a machine that 45 will disintegrate the same with a minimum amount of wear upon the operative parts. This object is attained by providing a rotary head having on its upper face walls extending toward the rim of the head, the front face of 50 each wall being contained in a plane that is radial to the axis of the head. By this construction a maximum expulsive effect with minimum wearing effect is attained.

In carrying out this invention I provide a

machine having a rotary device adapted to 55 set up high centrifugal force in material fed thereto, and to discharge such material with great force against a solid surface whereby the inertia of the particles of the material is made effective to disintegrate or disrupt the 60 object thus impelled and intercepted.

An object of this invention is to construct an ore disintegrator and pulverizer of large capacity and comparatively small size which may be composed of comparatively 65 light pieces that may be disassembled from the machine and packed on pack animals on mountainous and other difficult roads.

A further object is to make provision whereby the values may be certainly recovered after having once reached the disintegrator and pulverizer.

It may be stated here that in some ores the 70 richest values are found in an impalpable dust which in the processes of disintegrating and pulverizing are carried into the 75 outer air and lost.

An object of this invention is to avoid any such loss.

The accompanying drawings illustrate the 80 invention.

Figure 1 is a side elevation of an apparatus embodying this invention. Parts are broken away for clearness of illustration. Fig. 2 is a plan of the same, parts being 85 broken for clearness of illustration. Fig. 3 is an enlarged broken plan detail of the disintegrator and pulverizer proper, omitting the cover. Fig. 4 is a fragmental vertical section of the same, on line x^4-x^4 , Fig. 3. 90 Fig. 5 is a section on line x^5-x^5 , Fig. 3. Fig. 6 is a perspective view of one of the plates forming the intercepting wall.

1 is a frame having a central projection 40 and an annular bowl-shaped cavity 2 and 95 provided with a surmounting ring 3 having an octagonal inner wall and a cover 4 forming a chamber 5 in which a rotary device 6 is mounted on a vertical shaft 7 projecting through the central projection and is adapted to be rotated at a very high speed by a pulley 8 driven by a belt 9 from a pulley 10 on a line shaft 11. Said rotary device is hollow, being composed of a plain imperforate base plate or head 12, a top plate 13, and projections 14 between said base plate and top plate and forming impelling wings for impelling the material that may

be fed into the space between the plates and also for impelling air which may be admitted freely into said space.

15 is a central inlet through the cover 4 and 16 is a central opening in the top plate 13 to admit into the space 17 above the head 12 the material to be disintegrated and pulverized and also air to supply the blast for freeing the disintegrated and pulverized 10 product from the bowl shaped cavity 2.

18 designates plates to form the intercepting faces against which the material expelled from the rotary device 6 will impinge. Said intercepting faces may be variously formed depending upon the character 15 of the material to be reduced. In the drawings said faces are roughened, being vertically corrugated as indicated in Figs. 3, 4 and 6. The corrugated faces 19 thus provided afford a series of intercepting surfaces 20 against which the material may impinge at various angles thereto, in some instances at right angles and in other instances at acute or obtuse angles; the effect 25 being that the material thrown off at a tangent from the rotary device 6 will impinge upon the surfaces, and owing to the high speed at which the head is rotated and the consequent high trajectory of the object or material, will become reduced to a 30 greater or less degree of fineness by the force of such impact.

Practical use demonstrates that much of the material is reduced to a fine powder, 35 and that some of the material may not be so reduced, and therefore in practical use I propose to use a plurality of machines in train, but as this is customary already with crushers and analogous machines, it is not 40 deemed necessary to show any except the initial machine. It is to be understood that the invention may be embodied in various sizes, and that I do not limit the same to any specific size.

45 The projections 14 of the rotary device may be variously constructed. In the drawings, blocks 20 are secured by bolts 21 having their heads countersunk into and passing through the top plate 4 and screwing 50 into the bottom plate 12 and fastened by nuts 22 on their lower ends.

23 is a detachable shoe of U-form adapted to seat on the blocks 20 from the inside. The same may be constructed of such size 55 as to be readily insertible through the opening 16 in the top plate to rest against the block 20.

By referring to Fig. 3, it will be noted from the curved arrow that the rotary 60 device is intended to rotate with the hands of a watch and consequently the right wall of the uppermost shoe in the view is the one which will act upon the material fed to the machine. The forward 65 face of each of the protecting shoes

23 of the blocks 20, is therefore the impacting face, and receives whatever wear may result from engagement with the wing of the material fed to the machine. It is important that the forward face of each of the wings 14 shall extend in radial lines, as indicated in Fig. 3 by dotted lines extending from said forward faces to the center of the shaft. The arrangement thus shown is found to give most satisfactory 75 results. By constructing and arranging the front face of each wall, so that the horizontal traces of said face are contained in planes radial to the head, the wearing effect upon such faces is minimized and the explosive 80 effect upon the material fed to the head is brought to a maximum. In case the shoe becomes worn on its forward face it may be withdrawn, turned upside down, and reinserted, thus bringing a new face to the 85 front.

The head 12 is provided with a flanged hub 24 which projects upward through the face of the head and rounded at the top to form a distributor for the material fed through the central opening 16 of the top plate 13. Said hub also serves to limit the size of the orifice leading into the ways between the wings 14; the purpose being to provide an opening of large capacity but of 90 such size that no object which cannot pass between the top plate and the head can lodge on the head. Another object of the distributor is to impart a measure of centrifugal force to the material fed into the opening 16, so that as the material enters the rotary device, such motion is first set up in a measure, thus bringing the material into the path of the wings 14 by which the same 95 is caught and impelled outward at high 100 speed.

It is to be understood that I do not limit the inner wall of the ring 3 to the octagonal form shown, but propose preferably to use some angular form of inner wall, and that the octagonal form is the form I deem 110 preferable. 25 designates shoulders at the bases of the several corners of the inner wall of said angular ring, the same being provided to support the ends of the plates 18 and to hold the plates at the level of the rotary device. Said plates project inwardly for a considerable distance beyond said shoulders, and a sheer open space 26 is thus provided below the bottoms of said plates; 115 the purpose being to so construct the machine that the material broken by contact with the inner face 19 of the wall shall fall unobstructed into the bowl 2, the bottom of which slants to the inclined outlet 27 120 underneath said wall from which the material operated upon shall be discharged. Such discharge is practically effected instantaneously after the disintegrating and 125 pulverizing takes place, and is carried on 130

by the blast of air which is impelled outwardly by the rotary device which acts on the principle of a blower.

The product passes through the outlet 27, 5 by means of a lateral pipe and a dust-collector 28 is provided to receive the same. By this collector the product is finally discharged into a suitable receptacle, as the trough 29, whence it may be carried for further operations. By providing the pulverizer with a blower, and connecting the pulverizer with a dust-collector, the values contained in the dust may be delivered into the trough 29 or any other suitable receptacle 10 from which they may be carried to the cyaniding tanks or other devices for recovering the values. The air from the blower will finally escape from the central depending outlet 30 of the dust-collector, as indicated 15 by the curved lines shown in Fig. 1: The lateral pipe 27 opens tangentially into the space at the top of the body 28 of the dust collector, thus to cause the material to circle around the depending air outlet 30 whereby 20 the solids are caused to deposit and to discharge through the trough 29.

The rotary device is detachably mounted on the shaft 7 by means of the flanged hub 24 and a feather 31.

30 32 designates stud screws by which the parts of the head are secured together.

The frame 1 of the device may be of cast-iron or steel and provided with a step 33 having a socket 34 and a convex plate 35 at 35 the bottom of said socket. The lower end of the shaft 7 is provided with a hemispherical cavity 36 in which is seated a ball 37 which rests on the center of the convex face 35, thus forming an antifriction support for 40 the shaft 7.

38 designates babbitt in the step, and 39 designates babbitt in the center post 40 of the frame in which the shaft 7 rotates.

41 is an oil cup and 42 an oil duct cored 45 out in the frame to conduct oil from the cup to the shaft 7.

43 is an oil cup for the lower bearing of the shaft 7.

I claim:—

50 1. A centrifugal impact pulverizer comprising a rotary head having on its upper face blocks extending toward the rim of the head in planes radial to the axis of the head, a central hub spaced apart from said blocks, 55 U-shaped shoes seated on the blocks, and a wall spaced from and surrounding said head.

2. A centrifugal impact pulverizer comprising a base, a rotary head, blocks upon 60 the upper face of the rotary head and forming radial arms, double-faced U-shaped detachable reversible shoes fitting said blocks,

a plate having a central opening mounted upon said blocks, bolts inserted downwardly through the plate and the blocks and the 65 base to hold the shoes in place, plates to form intercepting faces for material expelled from the head, and a frame to support said head and plates.

3. In a centrifugal impact pulverizer, the 70 combination of a rotary head having a flat top and blocks extending up from said top and having flat front radial faces; a plate having a flat lower face parallel with said flat top fastened to the top of said blocks; 75 an annular wall around said plate having internal faces angularly disposed relative to each other, said faces being vertically fluted to intercept material expelled from said head; and an inclosure provided with a central opening above the annular plate, and with an open space, and with a peripheral outlet below said annular wall and head.

4. A centrifugal impact pulverizer comprising an inclosure having an internal 85 chamber, a central feed opening at the top and a peripheral outlet at the bottom; a shaft extending upwardly through the bottom of said inclosure at the center thereof; a head fixed on said shaft and mounted in 90 said chamber and spaced apart from the top and the bottom thereof, said head comprising a central hub, a circular plate fixed to said hub, wings fixed to the upper face of said circular plate, and an annular plate 95 fixed to the tops of said wings; said wings having detachable reversible U-shaped attachments having front radial faces; and an intercepting wall inside said inclosure and spaced apart from said head.

100 5. A centrifugal impact pulverizer comprising a frame having a bowl-shaped cavity provided with an outlet at the bottom, a ring having inwardly-projecting shoulders and surmounting the frame and surrounding the bowl-shaped cavity, impact plates supported by their inner corners upon the shoulders of the ring, a cover having a central inlet, a driven shaft extending upwardly through the frame and into the chamber 110 within the ring, a base plate secured to the shaft, a top plate having a central inlet, impelling wings having radial detachable reversible plane front faces and mounted between the base plate and the top plate, and 115 means securing the top plate and impelling wings rigidly to the base plate.

In testimony whereof, I have hereunto set my hand at Los Angeles California this 17th day of May 1907.

D. O. MARKS.

In presence of—

JAMES R. TOWNSEND,
LYNN S. ATKINSON.
